LENS GRINDER

Joseph Harry Martin, Roanoke, Va.

Application December 20, 1938, Serial No. 246,887

4 Claims. (Cl. 51—96)

The objects of this invention include the provision of a simple but effective mechanism whereby any curvature may be ground into a lens, without changing grinding wheels, and with a flat-surfaced wheel, novel means being supplied for mounting and actuating the movable parts in such a way that the result above alluded to may be accomplished.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Fig. 1 shows, in side elevation, a lens grinder constructed in accordance with the invention;

Fig. 2 is a top plan;

Fig. 3 is a fragmental section on the line 3—3 of Fig. 2;

Fig. 4 is a front end elevation;

Fig. 5 is a section on the line 5—5 of Fig. 1;

Fig. 6 is a section on the line 6—6 of Fig. 2;

Fig. 7 is a section on the line 7—7 of Fig. 6;

Fig. 8 is an elevation showing a modification;

Fig. 9 is a diagrammatic view referred to in connection with the description of the operation of the device.

For convenience in describing the relative locations of parts, that end of the machine to which the reference character A is applied will be considered the forward end, the rear end of the machine being marked by the reference character B.

The device forming the subject matter of this application comprises a bed 1 (Fig. 1) secured by legs 2 to a table 3. Near its forward end (Fig. 45) 2) the bed 1 is supplied with a laterally extended and upwardly projecting bearing standard 4 (Fig. 4) and in the bearing 4, a shaft 5 is journaled, the shaft being disposed transversely with respect to the length of the machine. A grinding wheel 6 is secured to the inner end of the shaft 5 and is disposed in the longitudinal axis of the machine as shown in Fig. 2.

The shaft 5 is supplied (Fig. 4) at its outer end, 55 with a worm 7, meshing with a worm wheel 8

journaled on a shaft 9 carried by an arm 10 projecting outwardly from the bearing standard 4.

A drive shaft 11 (Fig. 2) is supported for rotation in any suitable way (not shown) and is located below the table 3. A belt and pulley drive 12, depicted in Figs. 1 and 2, constitutes means whereby rotation is imparted to the shaft 5 and the grinding wheel 6 from the shaft 11.

A slide or support 14 (Fig. 3) is mounted for right line adjustment, toward and away from the 10 grinding wheel 6, in a guideway (Fig. 5) formed in the bed 1. For the adjustment of the slide 14, toward and away from the grinding wheel 6, there is provided such a mechanism as a feed screw 15 (Fig. 3) threaded into the slide 14, and held for 15 rotation but against longitudinal movement in the rear end of the bed 1. An elongated base member 16 (Fig. 2) is located above the slide 14 and bed 1, and intermediate its ends, the base member 16 is mounted to swing horizontally, and transversely of the plane of rotation of the grinding wheel 6, on a fulcrum screw 17 (Fig. 3) carried by the slide 14.

A bracket 18 (Figs. 1 and 4) is secured to the forward end of the base piece 16 and may be 25 considered part thereof. On the forward portion of the bracket 18 (Figs. 1 and 4) there is secured an upstanding post 19. A transverse pitman 20 (Figs. 4 and 2) is provided, the inner end of the pitman 20 being connected by a ball and socket joint to the post 19. Figures 4 and 1 show that a crank 21 is connected to the worm wheel 8, to turn therewith. The outer end of the pitman 20 is connected at 22 (Fig. 4) to the crank 21, for adjustment longitudinally of the crank.

The numeral 23 marks a carriage (Figs. 1 and 4), the carriage comprising an elongated base 24 and upwardly projecting standards 25. As shown in Figs. 4 and 5, for instance, the base 24 of the carriage 23 is mounted on the member 16 for adjustment longitudinally thereof, toward and away from the grinding wheel 6. A set screw 26 or other holding device (Fig. 1) carried by the base 24 of the carriage 23, maintains the carriage in any position to which it may have been adjusted, lengthwise of the member 16. Figure 2 shows that at one side the base 24 of the carriage 23 is provided with a longitudinal scale 27, adapted to cooperate with an index 28 secured to the edge of the base piece 16.

The standards 25 of the carriage 23 carry a fulcrum pin 29 (Fig. 2) on which a lever or guide 30 is mounted, between the standards 25, for vertical swinging movement, that is, in a direction at right angles to the axis of rotation of the grind-

ing wheel 6. Figure 5 shows that the lever 30 is trough-shaped in cross section.

Mounted for longitudinal adjustment in the trough-shaped lever 30 is the shank 31 (Figs. 1, 2 and 5) of a work carrier 32, including an arcuate head 33 (Fig. 1) convexed longitudinally toward the grinding wheel 6. The lens blocks L which are to be ground, are cemented or secured otherwise to the head 33 of the work carrier 32. It appears in Fig. 2 that shank 31 of the work carrier 32 is supplied with an elongated slot 34, cooperating with a holding device 35 on the lever 30, to retain the work carrier 32 in any position to which it may have been adjusted lengthwise. On the upper surface of the lever 30 there is a longitudinal scale 36 (Fig. 2), cooperating with an index 37 on the shank 31 of the work carrier 32.

Figures 1 and 6 show that a transverse shaft 38 is mounted to turn in a lateral tubular bearing 39 (Fig. 2) which is carried by one of the standards 25 of the carriage 23. The shaft 38 is driven from the power shaft 11, by a belt and pulley connection 40, shown in Figs. 2 and 1.

A pinion 41 (Figs. 6, 4 and 5) is secured to the inner end of the shaft 38 and meshes with a gear wheel 42, journaled on a stub shaft 43 (Fig. 7) mounted in one of the standards 25 of the carriage 23. The gear wheel 42 is supplied with a circular, eccentric track 44 (Fig. 6) receiving a roller projection 45 (Fig. 7) carried by the lever 30 (Fig. 1) and located behind the element 28 on which the lever swings vertically with respect to the carriage 23.

By means of the feed screw 15 of Figs. 1 and 3, the slide 14 can be adjusted to bring the lens blocks L up to the grinding wheel 6, the feed screw constituting means for producing relative movement between the work carrier 32 and the wheel 6, to position the lens blocks L properly for grinding. When the slide 14 is advanced with respect to the grinding wheel 6, the parts participating in that movement are the base member 16, the carriage 23, the lever 30 and the work carrier 32.

As to the rotation of the grinding wheel 6, that operation is brought about by the belt and pulley drive 12 of Figs. 1 and 2, the grinding wheel shaft 5, and the drive shaft 11.

The lateral swinging movement of the base member 16 (Fig. 2) on the pivot screw 17 that is carried by the slide 14, is accomplished by a train of parts including the bracket 18 (Fig. 1) on the forward end of the base member 16, the post 19 of Fig. 4, the pitman 20, the connection 22, the crank 21, and the worm wheel 8, the worm wheel being rotated by the worm 7 on the grinding wheel shaft 5.

The vertical swinging movement of the work carrier 32 is produced by a train of parts including the drive shaft 11 of Fig. 2, the belt and pulley drive 40 of Fig. 1, the shaft 38, the pinion 41 (Fig. 6) the gear wheel 42 supported at 43 on one of the standards 25 of the carriage 23, the eccentric groove or track 44 on the pinion 42, and the roller projection 45 which is carried by the lever 30 of Fig. 1, vertical tilting movement being imparted to the lever 30, on its fulcrum 29, the work carrier 32 participating in the vertical tilting movement of the lever 30.

The character r may be taken to represent the radius of curvature longitudinally of the axis Y-Y of Fig. 9, the origin of the radius r being the fulcrum screw 17 (Figs. 1 and 3) whereby the base member 16 is connected to the slide 14.

The character R may be taken to represent the radius of curvature along the axis X-X of Fig. 9, the origin of the radius R being the fulcrum pin 29 that connects the lever 30 to the standards 25 of the carriage 23. The grinding to produce curvature on the radius r is brought about by the lateral swinging movement of the base member 16 on the fulcrum screw 17 of Figs. 2 and 1, and the grinding to produce the curvature on the radius R is brought about by the vertical swinging movement of the lever 30 and the work carrier 32 with respect to the fulcrum 29 of the lever.

The radius R can be varied in length by shifting the shank 31 of the work carrier 32 in the trough-shaped lever 30, longitudinally thereof, the holding device 35 being set up to hold the shank 31 in any position to which it may have been adjusted. To facilitate this operation, a reading may be taken by means of the scale 36 and the index 37 of Fig. 2.

The radius r can be adjusted as to length by shifting the work carrier 32 lengthwise of the base member 16, the set screw 26 being tightened to hold the adjustment attained. To facilitate this operation, a reading may be taken by means of the index 28 and the scale 25 of Fig. 2.

Lens blocks for the kind of work done in the machine herein disclosed, come to the optician from the manufacturer with the inside surface (the surface cemented to the head 33 of the work carrier 32) finished to a minus six diopter curve. Figure 2 shows the machine set for grinding a piano lens. The index 28 registers with the "6" mark on the scale 27, and the index 37 registers with the "6" mark on the scale 36. The outside of the lens block will be ground to a plus six diopter curve, but since the inside curve is a neutralizing, minus six diopter curve, the resulting product will be a piano lens.

In order to grind a piano-cylinder, the radius R, representing the vertical swing of the work carrier 32 longitudinally of the axis X-X, remains unchanged, the index 37 cooperating with the "6" mark on the scale 36. The radius r , representing the horizontal swing of the base member 16 and all parts carried by it, longitudinally of the axis Y-Y, is changed, say by moving the carriage 23 until the index 28 cooperates with the "7" mark on the scale 27. The resulting product is a plus one diopter cylinder.

In order to grind a compound surface, the work holder 32 is moved until, for example, the index 37 cooperates with the "7" mark on the scale 36, the radius R being altered. The carriage 23 is moved until, for instance, the index 28 cooperates with the "8" mark on the scale 27. The resulting product will have a plus one diopter sphere combined with a plus one diopter cylinder.

The foregoing examples make manifest the possibilities of the machine in grinding curves other than those specified. Especial attention is directed to the fact that the device grinds a cylinder and a sphere on the same surface in one operation in an arc, the origin of the radius of the arc in Fig. 1 being the fulcrum member 29, and the origin of the radius of the arc in Fig. 9 being the axis of rotation of the shaft 29a.

The construction of the machine is such that any desired curvature may be ground, regardless of the shape of the wheel 6, that is, whether the wheel is flat, convexed transversely at its periphery, or even if the wheel 6 was of irregular shape, considered transversely of its periphery. There is no occasion for changing the grinding wheel 6.

because it happens to be somewhat out of condition at its circumference. The curves of the lens surface do not depend upon the configuration of the grinding wheel.

5 In Fig. 8 of the drawings, parts hereinbefore described have been designated by numerals already used with the suffix *a*. In this form of the invention, the fulcrum member 29 of Fig. 1 becomes a power driven shaft 29*a*, operated by a 10 pulley 46 and a belt 47, the work carrier 32*a* being a wheel, to the periphery of which the lens blocks are attached. The work carrier 32*a* receives continuous rotary motion, instead of the oscillating motion imparted to the work carrier 15 32 of Fig. 1, but in either form of the invention, the lens blocks are presented to the grinding wheel.

What is claimed is:

1. In a machine for grinding lenses of different 20 curvatures on a single grinding wheel, a grinding wheel, means for mounting the grinding wheel for rotation about an axis, a support, a base member, pivot means mounting the base member on the support for swinging movement in a plane disposed substantially parallel to the axis of rotation of the grinding wheel, a carriage, means 25 for mounting the carriage on the base member for right-line adjustment toward and from the pivot means, a lens carrier including a part holding a lens block in operative relation to the periphery of the grinding wheel, and means for so mounting the lens carrier on the carriage that said part of the lens carrier can move in an arc 30 and in a plane substantially at right angles to the axis of rotation of the grinding wheel, the lens carrier participating in the aforesaid movement of the carriage, toward and from the periphery of the grinding wheel, and participating in the aforesaid right-line adjustment of the carriage 35 with respect to the pivot means.

40 2. A machine for grinding lenses of different curvatures on a single grinding wheel, constructed as set forth in claim 1, in combination with mechanism independent of the means for mounting the carriage on the base for right-line ad-

justment toward and from the pivot means, for mounting the support and the grinding wheel for relative movement toward and away from each other, thereby to secure a grinding relation between the grinding wheel and a lens block on said 5 part of the lens carrier.

3. A machine for grinding lenses of different curvatures on a single grinding wheel, constructed as set forth in claim 1, and wherein the means for mounting the lens carrier as set forth in 10 claim 1 is a guide supported on the carriage for tilting movement about an axis substantially parallel to the axis of rotation of the grinding wheel, the lens carrier embodying an elongated shank, and means for mounting the shank for longitudinal 15 adjustment on the guide.

4. In a machine for grinding lenses of different curvatures on a single grinding wheel, a grinding wheel, means for mounting the grinding wheel for rotation about an axis, a support, 20 a base member, pivot means mounting the base member on the support for swinging movement in a plane disposed substantially parallel to the axis of rotation of the grinding wheel, a carriage, means for mounting the carriage on the 25 base member for right-line adjustment toward and from the pivot means, a guide mounted on the carriage for oscillating movement about an axis disposed substantially parallel to the axis of rotation of the grinding wheel, a lens carrier 30 including a part holding a lens block in operative relation to the periphery of the grinding wheel, the lens carrier participating in the aforesaid right-line adjustment of the carriage with respect to the pivot means, means for holding the 35 lens carrier on the guide in adjusted positions with respect to the axis of oscillating movement of the carriage, and mechanism for imparting oscillating movement to the guide, said mechanism comprising a driven wheel mounted to rotate on the carriage and having an eccentric track, the guide having a projection engaged with the track.

JOSEPH HARRY MARTIN. 45
